ELECTRIC CONDENSER

James L. Finch, East Rockaway, N. Y., assignor
to Radio Corporation of America, a corporation
of Delaware

Application December 21, 1940, Serial No. 371,073

6 Claims. (Cl. 175—41)

This invention relates to a new and useful electric condenser of the type having an internal fluid dielectric between the electrodes which may be maintained with or without pressure.

An object of this invention is to provide an improved condenser casing and terminal insulator construction.

Another object of this invention is to provide a casing and insulator construction wherein the fluid dielectric when placed under pressure will tend to seal the joint between the insulator and the inside wall of the casing more tightly upon an increase of pressure.

A feature of this invention is the novel arrangement of an insulator which is placed within the casing in such a manner that a shouldered end portion of the insulator compresses gasket material which bears against the inside wall of the casing.

Another feature of this invention is the novel method of centering the insulator axis with respect to the axis of the condenser casing.

Condensers of the fluid type are known in the prior art. The condenser insulator, however, is most usually placed outside of the casing and has a flange which is arranged to extend beneath a clamp ring and a gasket member which is secured to the outside of the casing by any suitable means in order to seal the joint between the insulator and casing. In such a construction, however, there is a tendency for the pressure within the casing to expand the clamp ring and gasket and thus give rise to undesirable leakage of the fluid pressure. The improved construction of my invention prevents fluid pressure leakage by placing the insulator flange portion within the casing and placing a gasket between the insulator and the inside wall of the casing so that an increase of fluid pressure seals the casing more tightly.

Condensers of my invention are primarily directed to condensers of the compressed air type, such as disclosed in the Hansell et al. Patent #2,192,062, issued Feb. 27, 1940, and although for the purpose of more clearly indicating my improved seal, only condensers of the fixed electrode type will be described, although it is to be understood that this invention will apply equally as well to variable condensers. Also, a dielectric of liquid rather than gas may be employed. The liquid or gas may be maintained at atmospheric pressure, although I prefer to employ in condensers of my invention a fluid pressure which is maintained between 150 and 200 lbs. per square inch.

This invention will best be understood by referring to the accompanying drawing, in which:

Fig. 1 is a longitudinal section of the condenser of my invention; and

Fig. 2 is a bottom view of Fig. 1.

Referring now in detail to the drawing, the condenser casing 1 is made preferably from extra heavy brass pipe having its upper end 1a shaped over to form an inwardly extending shoulder portion by hammering over a steel form. The inner portion of the upper end is accurately turned to fit a tapered shouldered portion on insulator 2. The bottom portion of the casing is threaded at 1b to receive a flange base ring 3. An internal threaded portion 1c is threaded to receive an insulator adjusting ring 4. The inner surface of casing 1 between portions 1c and 1b is accurately ground and polished to prevent brushing to adjacent electrodes and thus forms one of the electrode surfaces of the condenser. The insulator 2 is assembled within the casing so that its tapered shoulder portion 2a bears against the tapered portion 1a of the casing. The tapered portions 1a and 2a are coated with a heavy paste of "Fostoria Tight Seal." A lead gasket 5 is provided to prevent leakage of the internal fluid, also, entry of air and moisture from the outside atmosphere. The axis of insulator 2 must be accurately maintained at the same axis of the casing for the reason that condensers of this type are employed in circuits having relatively high voltages. Therefore, it is absolutely necessary that the electrodes be maintained in exact concentric relationship, and in order to maintain the insulator in this exact relationship, there is provided a bearing clamp ring 6 which is placed beneath the flange portion of insulator 2 and is arranged to be clamped between adjusting ring 4 by means of eight safety hollow set screws 7 having a cup point. Set screws 7 also serve to clamp insulator 2 against the inside wall of the casing by applying pressure thereto. To further prevent air leakage and also damage to the insulator, a second lead gasket 8 is interposed between insulator 2 and bearing ring 6. The lower end of the casing is provided with a base plate 9 and is retained in a fluid-tight manner by means of a plurality of set screws 10. A suitable gasket 11 is interposed between base ring 3 and casing 1. The insulator 2 has a relatively long narrow cone-shaped inner surface which provides a large electrical creepage surface as condensers of this type are particularly desirable for use in ultra-high frequency circuits and with such an arrangement the condenser is capable of withstand-

ing 30,000 peak volts for a relatively long period. A second electrode surface 12 is threaded to the inside portion of base plate 9. The upper portion of inner electrode 12 is closed by means of a cover plate 13 which is soldered at a point 14. A relatively small aperture 15 in cover 13 gives an improved safety factor to the condenser by reducing the explosion effects due to rapid expansion of the fluid within the casing when any part of the condenser structure fails. The space within members 12 and 13 serves as a storage tank, also, the space within member 12 encloses suitable filtering means 16 to filter out moisture and dust and thus greatly improves the voltage rating of the condenser and extends its useful life. A more complete and detailed description of this arrangement will be found disclosed in the Usselman Patent. #2,210,050, issued Aug. 6, 1940. A third electrode surface 16 is supported by being soldered to a disc member 17, the latter being secured to a shaft or terminal electrode 18 by means of three flat-head screws 19 which pass through a recessed portion 17a in member 17. The upper portion of shaft 18 seats against a shouldered portion 20 on insulator 2. A lead gasket 21 is interposed between the shouldered portion 20 and the insulator 2. A brass collar or terminal washer 22 is threaded on the extreme upper end of shaft 18 and is retained in place by a clamp nut 23, leakage of the fluid within the condenser being prevented by means of a relatively heavy lead gasket 24 which is interposed between the top of insulator 2 and the underside of terminal washer 22. For making electrical connection to the central electrode terminal of the condenser, a plurality of threaded apertures 25 are provided. Casing 1 is equipped with an air valve 26 and cap 27, valve 26 being soldered to casing 1 at a threaded portion 28 to prevent leakage of air within the casing. In order that the dielectric fluid within the casing which may be air, gas or compressed liquid under pressure may be accurately determined, a pressure gauge 30 is provided having a scale with indications from zero to three hundred pounds pressure.

Although only one modification of this invention is disclosed, it is to be distinctly understood that it should not be limited precisely thereto.

What is claimed is:

1. An electric condenser capable of operating at an internal fluid pressure different from atmospheric pressure, said condenser including an approximately cylindrical casing, means near one end of said casing forming an inwardly extending annular shoulder faced toward the higher pressure and held against movement axially of said casing in a direction toward the lower pressure, said inwardly extending shoulder being formed by an inwardly bent marginal end portion of said casing itself, a dielectric closure member extending across said casing near said end and seated substantially against the side of said shoulder which is toward the higher pressure, so that an increase in the fluid pressure difference within and without said casing will tend to seat said dielectric member more firmly against said shoulder, means closing the opposite end of said casing in a substantially fluid tight manner, a first metallic electrode mounted within said casing, and a second metallic electrode spaced from the first electrode and supported from said dielectric member.

2. An electric condenser capable of operating at an internal fluid pressure different from at-

mospheric pressure, said condenser including a casing, a first metallic electrode mounted concentric within said casing, said casing having an inwardly extending shoulder portion formed by the casing itself, an insulator having a tapered shoulder portion of substantially the same contour as the inwardly extending shoulder portion of said casing, said tapered shoulder portion of said insulator seated substantially against the side of said inwardly extending shoulder which is toward the higher pressure, so that an increase in the fluid pressure difference within and without said casing will tend to seat said insulator more firmly against said inwardly extending shoulder, a shaft supported from said insulator and extending within said casing, and a second metallic electrode mounted on said shaft within said casing and concentrically spaced from said first electrode, and means within said casing for applying pressure to retain said insulator in a central location within said casing to give sealing protection against ingress or egress of fluid pressure between said insulator and said casing.

3. An electric condenser capable of operating at an internal fluid pressure higher than the outside atmospheric pressure, said condenser including a casing, a first metallic electrode mounted within said casing, said casing having an inwardly extending shoulder portion formed by the casing itself, a threaded portion within said casing, a dielectric element forming a closure seated substantially against the side of the inwardly extending shoulder portion of said casing which is toward the higher pressure and making a tight sealing joint therewith so that an increase in fluid pressure difference within and without said casing will tend to seat said dielectric element more firmly against said shoulder, a threaded adjusting ring secured to the threaded portion of said casing, means on said ring to clamp said dielectric element within said casing, a shaft supported from said dielectric element and extending within said casing and a second metallic electrode mounted on said shaft within said casing and spaced from said first electrode.

4. An electric condenser capable of operating at an internal fluid pressure higher than the outside atmospheric fluid pressure, said condenser including a casing, a first metallic electrode mounted within said casing, said casing having an inwardly extending shoulder portion formed by the casing itself, a threaded portion within said casing, a dielectric element forming a closure seated substantially against the side of the inwardly extending shoulder portion of said casing which is toward the higher pressure and making a tight sealing joint therewith so that an increase in fluid pressure difference within and without said casing will tend to seat said dielectric element more firmly against said shoulder, a threaded adjusting ring secured to the threaded portion of said casing, a clamp ring located intermediate said dielectric element and said threaded adjusting ring, means in said threaded adjusting ring to apply pressure to said clamp ring to clamp said dielectric element within said casing, a shaft supported from said dielectric element and extending within said casing and a second metallic electrode mounted on said shaft within said casing and spaced from said first electrode.

5. An electric condenser capable of operating at an internal fluid pressure higher than the outside atmospheric fluid pressure, said condenser including a casing, a first metallic elec-

trode mounted within said casing, said casing having an inwardly extending shoulder portion formed by the casing itself, a threaded portion within said casing, a dielectric element forming a closure seated substantially against the side of the inwardly extending shoulder portion of said casing which is toward the higher pressure and making a tight sealing joint therewith so that an increase in fluid pressure difference within and without said casing will tend to seat said dielectric element more firmly against said shoulder, an adjusting ring having a threaded flanged portion secured to the threaded portion of said casing, means passing through said ring to clamp said dielectric element in said casing, a shaft supported from said dielectric element and extending within said casing, and a second metallic electrode mounted on said shaft within said casing and spaced from said first electrode.

6. An electric condenser capable of operating at an internal fluid pressure higher than the outside atmospheric fluid pressure, said con-

denser including a casing having an inwardly extending shoulder portion formed by the casing itself, a threaded portion within said casing, a first metallic electrode mounted within said casing, a dielectric element forming a closure seated substantially against the side of the inwardly extending shoulder portion of said casing which is toward the higher pressure and making a tight sealing joint therewith so that an increase in fluid pressure difference within and without said casing will tend to seat said dielectric element more firmly against said shoulder, a threaded adjusting ring secured to said threaded portion within said casing, means including screws passing through threaded apertures in said ring to clamp said dielectric element within said casing, a shaft supported from said dielectric element and extending within said casing, and a second electrode mounted on said shaft within said casing and spaced from said first electrode.
